UNITED STATES PATENT OFFICE

ARTHUR WALTER, OF LIVERPOOL, NEW YORK

COMBINATION CHAIR AND BED

Application filed May 7, 1930. Serial No. 450,498.

The present invention relates to a combination chair and bed and has for its prime object to provide a structure which is exceedingly simple, inexpensive to manufacture, strong and durable, compact and convenient in its arrangement of parts, easy to manipulate, and thoroughly efficient and reliable in use and operation. The device disclosed herein may be utilized both as a combination for 10 actual use or as a toy.

With the above and numerous other objects in view as will appear as the description proceeds, the invention resides in certain novel features of construction, and in the combination and arrangement of parts as will be hereinafter more fully described and claimed.

In the drawings:

Figure 1 is a longitudinal section through the device embodying the features of my invention,

Figure 2 is a top plan view of the device embodying the features of my invention,

Figure 3 is a sectional view through the device shown as used as a chair,

Figure 4 is a side elevation thereof.

Referring to the drawings in detail it will be seen that numeral 5 denote a pair of side panels adapted to rest on the floor or the like to rise upwardly thereof in spaced parallel 30 coextensive relationship with the seat panel 6 disposed between the side panels 5 intermediate the upper and lower ends thereof being somewhat closer to the upper ends thereof.

A leg panel 7 extends downwardly between the panels 5 from the forward portion of the panel 6 inclining downwardly and forwardly. The panels 5 at their front edges adjaes their bottom are provided with upwardly and forwardly inclined extension arms 8 between 40 which is a foot rest panel 9.

The rear edges of the panels 5 below the panel 6 are curved inwardly as is indicated by numerals 10. A back panel 11 is hingedly connected at 12 with the rear edge of the panel 45 6 and has side panels 14 mounted thereon.

These side panels 14 have at their lower edges extensions 15 which are curved to fit snugly the curved edges 10 when the panel 11 is in extension of the panel 6 as shown in Figures 50 1 and 2 but the panel 11 may be raised up-

wardly to the position shown in Figure 3 at which time the extensions 15 function as legs to engage the floor thereby holding the back in an upright position so that the device may be used as a chair. Arcuate slotted members 55 16 are pivoted as at 17 on the side panels 14 and receive pins 18 projecting from the side panels 5 so as to limit the swinging movement of the back with respect to the bottom panel 6.

It is thought that the construction, operation, utility and advantages of this invention will now be quite apparent to those skilled in this art without a more detailed description thereof.

The present embodiment of the invention 65 has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of 75 the invention as hereinafter claimed or sacrificing any of its advantages.

Having thus described my invention, what I claim as new is:

1. A device of the class described comprising a pair of side panels disposed in spaced parallel coextensive relationship to each other and adapted to rest on the floor or the like to rise vertically therefrom, a seat panel extending between the side panels, a back panel hinged to the rear edge of the seat panel, side panels on the back panel having extensions to engage the first mentioned panels to hold the back panel in coextension of the seat panel and for engagement with the floor to retain the back panel at an angle to said seat panel.

2. A device of the class described comprising a pair of side panels disposed in spaced parallel coextensive relationship to each other and adapted to rest on the floor or the like to rise vertically therefrom, a seat panel extending between the side panels, a back panel hinged to the rear edge of the seat panel, side panels on the back panel having 100

extensions to engage the first mentioned panels to hold the back panel in coextension of the seat panel and for engagement with the floor to retain the back panel at an angle 5 to said seat panel, the first mentioned side panels having forwardly directed extensions at their lower ends and a foot rest therebetween.

3. A device of the class described comprising a pair of side panels disposed in spaced parallel coextensive relationship to each other and adapted to rest on the floor or the like to rise vertically therefrom, a seat panel extending between the side panels, a back 10 panel hinged to the rear edge of the seat panel, side panels on the back panel having extensions to engage the first mentioned panels to hold the back panel in coextension of the seat panel and for engagement with 15 the floor to retain the back panel at an angle to said seat panel, the first mentioned side panels having forwardly directed extensions at their lower ends and a foot rest therebetween, arcuate slotted members pivotally engaged on one pair of side panels and receiving pins projecting from the other side 20 panels.

4. A combination bed and chair comprising a pair of side members, a fixed seat panel 25 arranged between said side members, a back panel hinged to said seat panel and capable of swinging movement relative thereto, said back panel provided with extensions adapted to engage said sides when the back is swung 30 to a substantially horizontal position, and to engage the floor when the back panel is swung to a substantially vertical position for retaining said back panel in the last-mentioned 35 position.

40 In testimony whereof I affix my signature.
ARTHUR WALTER.
